UNITED STATES PATENT OFFICE

2,530,168

APPARATUS FOR MAKING STEMS FOR
ELECTRICAL DEVICES

William John Knochel, East Orange, and Charles Wiener, Bloomfield, N. J., assignors to Westinghouse Electric Corporation, East Pittsburgh, Pa., a corporation of Pennsylvania

Application September 24, 1946, Serial No. 698,914

7 Claims. (Cl. 49—2)

1

This invention relates to stem making and, more particularly, to the prevention of over-oxidation of stem leads during manufacture.

The principal object of our invention, generally considered, is to facilitate the manufacture of stems, and particularly those with unbeaded "Kovar" leads, as well as avoiding shrinkage due to over-oxidation of such leads.

Another object of our invention is to reduce the time that such "Kovar" leads are exposed to oxidizing heat during incorporation in a stem, thereby preventing over-oxidation.

A further object of our invention is to avoid over-oxidation of "Kovar" leads, by speeding up the pressing of stems incorporating the same, and following a first pressing by another a few seconds before the stem-making machine indexes to the next position.

A still further object of our invention is to improve on the machine for making stems, and particularly those having unbeaded "Kovar" leads, by transferring the operating means for the pressing jaws from the Geneva drive shaft cam to a larger cam on the continuous driving shaft which operates the gear on the Geneva shaft, and adjusting such in position on said drive shaft.

An additional object of our invention is to include a second frog on said driving shaft cam, and provide for varying it in position so as to control the time between pressing operations in the manufacture of stems.

Other objects and advantages of the invention will become apparent as the description proceeds.

Referring to the scale drawing:

Figure 1 is a plan of a stem-making machine embodying our invention.

Figure 2 is a fragmentary elevational view of said machine, on a larger scale and with a part in vertical section.

Figure 3 is a fragmentary horizontal sectional view on the line III—III of Figure 2, in the direction of the arrows.

Figure 4 is a fragmentary elevational view, corresponding to Figure 2, but showing a subsequent position in which the pressing jaws are together in pressing engagement with positioned stem elements.

Figure 5 is a view, corresponding to Figure 4, but showing a subsequent position in which the jaws have been withdrawn from pressing engagement with a formed stem.

Figure 6 is a diagram illustrating the sequence of events in forming a stem in accordance with our invention.

2

Figure 7 is an elevational view of a completed stem.

The present invention is concerned with the prevention of over-oxidation of leads for electrical devices, and particularly of unbeaded "Kovar" leads during stem making.

In making stems, in accordance with our invention, all of the conventional steps are employed except that the pressing time, which occurs after the machine indexes at the final heating and pressing operation point, is reduced to a degree that over-oxidation of the lead wire cannot take place. In accordance with the normal procedure, a long heat soaking is employed after the pressing jaws operate. We have, therefore, provided for a second pressing operation to occur a few seconds before the machine indexes to the next position.

In accordance with our invention, such a second pressing operation is designated to perform two functions:

1. It makes positive the complete flow of glass around the lead wires.
2. It shapes the stem and prevents heavy non-uniform sections of glass from forming, which later causes cracked presses.

In order to effect such control, the normal stem machine has been modified. Previously, the pressing time was controlled by a frog on a small cam that was located on the drive shaft for the Geneva and which, therefore, could only operate during the indexing period. This meant that a stationary period was existing, the pressing operation could only take place approximately three seconds before the machine indexed to the next position, and there was no mechanical means available for time adjustment.

In accordance with our invention, we apply a large-diameter cam to the continuous driving shaft which causes the Geneva drive shaft to move. By proper positioning of a frog on the cam, the first pressing operation can be controlled from one second after to one second before the indexing takes place. A second pressing operation is caused to occur by the addition of a second frog to the cam, the position of which can be varied, and the time between the first and second pressing operations closely controlled.

Referring to the drawing in detail, like parts being designated by like reference characters, there is illustrated a stem-making machine 11, comprising a conveyor 12 rotatable about a normally upright standard or shaft 13, and supported on the top member of a table, base, or other support 14. The hub 15 of said conveyor 12 carries

a Geneva driven member or star wheel 16 and rests on a plate or washer 17, in turn supported on anti-friction means, such as a ball or roller bearing 18.

The conveyor carries a plurality of heads 19 having upwardly opening pockets 21, each carrying a split generally cylindrical plug 22, in each of which may be held leads 23 and 24, and on each of which may be supported a flare tube 25 and an exhaust tube 26. Although not limited, thereto, we are assuming that the leads 23 and 24 are made of "Kovar," or similar oxidizable metal, as they are the kind that we are especially concerned with for the prevention of oxidation.

In the present embodiment, the conveyor 12 is operated by power means such as a motor, or other prime mover 27, having a pulley 28 over which a belt 29 passes to a pulley 31 on a shaft 32, carrying a worm 33 meshing with a gear 34 on a continuous drive shaft 35. Said drive shaft 35 is mounted for rotation in the table or support 14, and a bracket 36 extending from a portion thereof, as shown most clearly in Figure 2. Said shaft 35 carries a gear 37 which is mutilated by having teeth removed therefrom around a large proportion of its circumference, as illustrated, so that the drive gear 38 with which it engages, and which is mounted on the Geneva drive shaft 39, is stationary for a considerable part of the operating time. The upper portion of the shaft 39 carries a Geneva-star-wheel operating member or driver 41, a portion 42 of which sequentially engages the slots 43 in the Geneva 16 to effect intermittent rotation of the latter.

Mounted above the final heat and pressing station 44 are a pair of pressure jaws 45 and 46, pivoted to an arm 47, projecting from the upper portion of the standard or shaft 13 about which the conveyor 12 rotates, as indicated at 48 and 49. These jaws are connected to a bracket 51, by means of links 52 and 53 pivoted respectively to said bracket 51 and bell-crank arms 54 and 55 projecting from the jaws 45 and 46, respectively. The bracket 51 is carried by a rod 56, reciprocating in the standard 13, and operated by a lever 57 pivoted to the base 14, as indicated at 58, urged upwardly by an operating spring 59, and bifurcated laterally and vertically at its end to receive said rod 56 and projections 61 on the lower portion thereof. The lever 57 carries a roller 62, pivoted as indicated at 63, and urged into engagement with a cam 64 carried on the lower end of the same shaft 35 that drives the conveyor 12. The cam 64 comprises a plate carrying a pair of frogs, 65 and 66, adjustably secured thereto, as by bolts 67 and 68 movable in arcuate slots 69 and 71, respectively.

Mounted on the support 14 are several gas pipes 12 terminating in burner nozzles adapted to provide fires 73, 74, 75, and 76, at preheating stations 77 and 78, final heating and pressing station 44, and annealing and exhaust tube opening station 79. The fires at preheating station 77 are relatively mild, those at station 78 are hotter, while those at station 44 are adapted to effect the final heating for softening the glass sufficiently for the pressing operations. The fires at station 79 are merely sufficient to allow for opening the exhaust tube and effecting annealing.

The operation of the machine for the practice of our invention may be as follows: All of the fires are lighted and a flare 25, an exhaust tube 26, and a pair of leads 23 and 24 are placed in the head at the station preceding preheating station 77 and labeled "charging" in Figure 1. As

the conveyor 12 is turned during operation by the drive motor 27, through the chain of gears previously described, the assembled stem parts successively index at stations 77 and 78, where they are sufficiently preheated, and then at station 44 where they are sufficiently softened by fires 75. At the proper time, say about six seconds after indexing, the pressing jaws 45 and 46 move, upon engagement of the frog 65 with the roller 62, causing descent of the rod 56, from the full to the dotted line position illustrated in Figure 2, where they squeeze the softened flare tube into engagement with the softened exhaust tube about the associated leads.

15 The pressing sequence is shown in Figure 6, where the complete cycle is indicated as taking seventeen seconds, beginning with the indexing jog 80, and the first pressing operation occurs, as represented by the jog 81 of the graph. Continued operation of the machine results in release of the jaws 45 and 46 to the full line position of 20 Figure 2. The next frog 66 then engages the roller 62, again causing the pressing arms 45 and 46 to engage the prepressed stem, as represented by the jog 82 on the graph of Figure 6, and as 25 illustrated in Figure 4, followed by release of the jaws as in Figure 5.

A few seconds after these pressing and release operations, the head carrying the formed stem 30 is moved to the next position, 79, where the exhaust tube is opened by a properly directed blast of air from a pipe 83, as shown in Figure 1 as indicated by the aperture 84 in Figure 7, and the formed stem subjected to the desired annealing treatment. This stem is then moved to and indexed at the next station, labeled "discharging," where it may be removed from the machine.

From the foregoing disclosure, it will be seen that we have improved on the manufacture of stems; first, by speeding up the machine from a cycle time of twenty-four seconds to one of seventeen seconds. While previously the pressing jaws acted about thirteen seconds after each head indexed, now the pressing jaws act about six and 35 fourteen seconds, respectively, after such indexing, with the possibility of varying the pressing time to any desired value. The change in cycle time allows for a gain of approximately 25% in production, while the change in pressing results 40 in a shrinkage decrease from between 50% and 75% to between $\frac{1}{2}\%$ and 1%. A metallurgical check has revealed that the quality of stems produced, in accordance with our invention, is 45 very good and that a great deal of latitude now exists in the control of lead wire oxidization.

Although a preferred embodiment of our invention has been disclosed, it will be understood that modifications may be made within the spirit and scope of the appended claims.

60 The Lempert et al. Patent No. 2,279,831, dated April 14, 1942, is referred to for the formula of "Kovar."

We claim:

1. Apparatus for making stems for electrical 65 devices comprising a conveyor for supporting and moving assembled glass stem parts and leads, fires for heating said parts, jaws for at one location performing all of the following operations: pressing said parts after being softened by heating 70 to consolidate them, and then after a continuation of said heating again pressing to effect a complete flow of glass around said leads and shaping of the stem, preventing heavy non-uniform sections of glass from forming, single power 75 means, mechanism between said power means and

conveyor for intermittently driving the latter, and mechanism between said power means and jaws for causing the latter to effect said double pressing operation.

2. Apparatus for making stems for electrical devices comprising means for heating an assembled glass flare, glass exhaust tube, and leads for a relatively short period of time until the glass parts are sufficiently softened for consolidation, and means comprising a power-operated plate carrying a pair of adjustable cam elements for at one location performing all of the following operations: pressing said softened glass parts to consolidate them about said leads, and shortly thereafter repeating the pressing operation.

3. Apparatus for making stems for electrical devices comprising means for heating an assembled glass flare tube, glass exhaust tube, and leads, for about six seconds, in a given position, until they are sufficiently softened for working, and means comprising a power-operated plate carrying a pair of adjustable cam elements for then at one location performing all of the following operations: pressing said parts to consolidate the flare and exhaust tube with respect to said leads, and repeating the pressing operation about eight seconds later, in order to make positive the complete flow of glass around the leads and shape the stem, preventing heavy non-uniform sections of glass from forming.

4. Apparatus for making stems for electrical devices comprising a conveyor, heads thereon for supporting assembled stem parts, means for heating said assembled parts, pressing jaws pivoted adjacent said conveyor to act on said parts after heating, means pivoting conveyor for rotation about a vertical axis, means for intermittently rotating said conveyor about said axis comprising a Geneva star wheel on said conveyor, a driver therefor, a shaft carrying said driver, a gear on said shaft, a drive shaft for said conveyor, a drive gear mounted on said shaft and mutilated so that it periodically engages and disengages with respect to the gear on said driver-carrying shaft, so that said conveyor is periodically indexed from station to station, a jaw-operating cam device mounted on said drive shaft and provided with adjustable cam elements, an operating arm, means pivoting said arm in cooperative association with said cam device, mechanism for conveying motion from said arm to said jaws, means to normally hold said jaws in open position, and means on said arm engaged by said adjustable cam elements for periodically closing said jaws to first effect consolidation and then effect shaping of each stem being manufactured.

5. Apparatus for making stems for electrical devices comprising a conveyor, heads thereon for supporting assembled stem parts, means for heating said parts, pressing jaws pivoted adjacent said conveyor to act on said parts after heating, means pivoting said conveyor for rotation about a vertical axis, means for intermittently rotating said conveyor about said axis comprising a Geneva star wheel on said conveyor, a driver therefor, a shaft carrying said driver, a gear on said shaft, a drive shaft for said conveyor, a drive gear mounted on said shaft and formed so that it periodically engages and disengages with respect to the gear on said driver-carrying shaft, so as to effect desired movement of said conveyor, a jaw-operating cam mounted on said shaft and

comprising a plate with a plurality of adjustable frogs secured thereto, an operating arm, means pivoting said arm in cooperative association with said cam, mechanism for conveying motion from said arm to said jaws, resilient means acting on said arm to normally hold said jaws in open position, and a roller pivoted to said arm and periodically engaged by said frogs for first closing and opening and then again closing and opening said jaws with respect to each group of assembled stem parts.

6. Apparatus for making stems for electrical devices comprising a conveyor, heads thereon for supporting assembled stem parts, means for heating said assembled parts, pressing jaws pivoted adjacent said conveyor to act on said parts after heating, a standard about which said conveyor rotates, a Geneva star wheel carried by said conveyor, a drive shaft, a drive gear mounted on said shaft and mutilated so that it periodically engages and disengages, a gear engageable by said mutilated gear, a shaft carrying said engageable gear, a driver on said shaft for said Geneva star wheel, a jaw-operating cam mounted on said drive shaft and comprising a plate with a plurality of adjustable elements secured thereto, and mechanism for conveying motion from said adjustable elements to said pressing jaws in order to cause them to close, open, and then again close and open with respect to each set of assembled stem parts while the latter are in softened condition.

7. Apparatus for making stems for electrical devices comprising a conveyor, heads thereon for supporting assembled stem parts, means for heating said assembled parts, pressing jaws pivoted above said conveyor to act on said parts after heating, a standard about which said conveyor rotates, a Geneva star wheel carried by said conveyor, a shaft for turning said conveyor, a Geneva star wheel driver mounted on said shaft, a gear mounted on said driver carrying shaft, a drive shaft, a drive gear mounted on said drive shaft and mutilated so that it periodically engages and disengages with respect to said driver-carrying shaft gear, a jaw-operating cam mounted on said drive shaft and comprising a plate with a plurality of adjustable frogs secured thereto, an operating arm, means pivoting said arm in cooperative association with said jaw-operating cam, mechanism for conveying motion from said arm to said pressing jaws, a spring acting on said arm to normally hold said jaws in open position, and a roller carried by said pivoted arm and periodically engaged by said frogs for closing said jaws against the force of said spring.
